UNITED STATES PATENT OFFICE

FRANK M. MAYER, OF BELLEFONTE, PENNSYLVANIA

GRINDING MILL FOR GRAINS

Application filed July 24, 1928. Serial No. 295,027.

This invention relates to improvements in grinding mills or machines particularly adapted for grinding corn, oats, barley, rye, wheat, and other grains of a similar nature. A prime object of this invention is to provide a vertically arranged grinding machine having an outer corrugated shell revolving in opposite direction to a cooperating cone shaped corrugated surface within the shell, thereby greatly increasing the grinding capacity in the machine and reducing the power consumption considerably. The grinding machine according to this invention is not intended primarily as a milling device for reducing to a fine degree, as required in flour and cereal milling, but is constructed principally for the purpose of heavy duty feed grinding and will reduce or grind whole corn, including corn on the cob after it has gone through a corn crusher, into feed for cattle, horses and hogs.

Another object of this invention is to provide a grinding machine consisting of a minimum number of parts, simple and inexpensive of construction and which includes a complete unit or grinding device in itself, having corrugated grinding plates or mantels, arranged to be easily removed for re-corrugating or repairs without in any manner disturbing the supporting members, the machine being also provided with a feeder member as well as a distributor, thereby assuring an even stream of grain to the grinding chambers.

A further object of this invention is to provide a complete grinding machine for grains including feeder and distributing members, the grinding elements comprising an outer shell, adjustably and rotatably mounted in the machine, and an inner cone-shaped member adapted to revolve in opposite direction to the shell, both the shell and cone shaped member being adjustable in relationship to each other.

Other objects of this invention will appear from the following detailed description of the device and as disclosed in the three sheets of drawings which are herewith made a part of this application.

In the drawings—

Figure 1 illustrates a vertical sectional view of the grinding machine disclosing the feeding, distributing, and grinding members in operative relationship.

Figure 2 represents a cross sectional view of the device taken along line 2—2 of Figure 1.

Figure 3 illustrates a cross sectional view of the grinding machine taken along line 3—3 of Figure 1.

Figure 4 represents a side elevational view of the corrugated cone shaped grinding member, disclosing the distributing means connected therewith for separating the grain elements just before grinding.

Figure 5 illustrates a bottom plan view of Figure 4.

Figure 6 represents a perspective view of the cap or supporting member for the distributing elements in attached relationship to the grinding cone.

Figure 7 illustrates a side elevational view of the grinding shell.

Figure 8 represents a top plan view of the grinding shell showing the corrugations therein.

Figure 9 represents a vertical sectional view of the grinding shell disclosing the driving gear in attached relationship thereto and the corrugations on the inner surface in operative position.

Figure 10 illustrates a sectional view of Figure 1 taken along line 10—10, disclosing the means for raising and lowering the grinding cone and shaft.

The grinding machine according to this invention includes a supporting structure consisting of side members 1 and 2, made of any suitable material, and adapted to have securely fastened thereto by means of bolts 3 and 4, suitably formed guiding and supporting brackets 5 and 6, which may be made of any proper material, such as sheet iron or otherwise.

A top frame member 7 is adapted to be attached or connected with the side members 1 and 2 in such a manner that it will function to support a feed and grain inlet spout consisting of a lead tube 8, extending from

some source of grain supply and delivering into a chamber 9, formed from a box shaped construction 10, which is securely supported on the frame member 7 by means of machine screws 11 or otherwise. The box shaped member 10 is preferred to be divided into chamber portions 9 and 12, the chamber portion 12 being utilized as a housing for the gear elements 13 and 14, while the chamber 9 is adapted to receive the grain as it delivers from the spout 8.

The gear 13 is keyed to a shaft member 15, which is rotatably mounted in the housing 10, as clearly disclosed at 16, that portion of the shaft 15 extending from the chamber 9 having securely mounted thereon a paddle member 17 for the purpose of breaking up and separating the grains just previous to its delivery through an auxiliary chute 18, extending below the supporting member 7 and through an opening 19 therein. The auxiliary chute 18 is adapted to be fastened to the supporting member 7 by means of element 20. A guiding or deflecting plate 21 is securely fastened to the under surface of the supporting member 7 by means of element 22 for the purpose of maintaining the particles of grain in their proper channel.

The main members of the grinding mill consist of a truncated cone shaped shell 23, made of cast iron or some other suitable material, and is adapted to be rotatably mounted on the supporting bracket portion 5 in any suitable manner such as by the ball bearings 24. Lock or set screws 25 are adapted to extend loosely through outwardly extending lug portions 26 from the ball bearing race member 26' for the purpose of holding the race firmly in position on the supporting member 5, after it has been properly located by means of adjusting screw 25'. The numeral 25' designates a plurality of set screws adapted to be mounted in suitable lug portions securely attached to the plate member 5, and arranged in such a manner that the shell 23 may be given sideway adjustability by the proper operation of the set screws 25', the ball bearing supporting members 24 being slidably positioned on the plate 5. The inner surface of the shell 23 is provided with a detachable corrugated plate 27, connected with the surface in some suitable manner as by tap screws 28. Securely fastened to the outer periphery of the shell 23 by means of elements 29 is a gear member 30, adapted to cooperate and mesh with a driving gear member 31, securely keyed to a shaft element 32, which is mounted in a journal bearing 33 attached to the supporting member 2 by means of plate 34.

The shaft element 32 is adapted to extend upwardly and have mounted at its upper end the gear 14, which coacts and meshes with a gear 13 for the purpose of driving the paddle member 17. Bracket or bearing portions

35, 36, and 37 are fastened to the supporting member 2 for the purpose of holding the shaft element 32 in rotative position therein. A shaft member 38 is rotatively mounted in a support 39, which is connected with and supported by a rod element 40, adjustably mounted in the supporting members 1 and 2. The support 39 is adapted to be provided with an enlarged portion 41 having a ball bearing 42 or otherwise positioned therein for the purpose of maintaining the shaft 38 in practically frictionless rotative position.

A collar portion 43 extends from the shaft 38 in order to form a proper bearing for the roller device 42. The upper end of the shaft 38 is rotatively mounted in a bearing 44, which is fastened to the frame member 7 by means of bolts 45 or otherwise. In the lower portion of the shaft 38 is preferably secured a longitudinal key member 46, which should be of sufficient length to receive in keyed relationship to the shaft a driving pulley 47, adapted to be driven from some suitable source of power by means of a plate 48, a sprocket wheel or pulley 49 for driving the shaft 32, the shell member 23, and the paddle 17. The sprocket wheel 49 is adapted to cooperate with wheel member 50, keyed to the shaft 32, the wheel members 49 and 50 being operably connected by means of a chain 51 or other suitable element 52.

The shaft 38 has securely mounted thereon in operative alignment with the shell 23 a truncated cone shaped member 52 having attached to its outer periphery a suitable corrugated plate 53, which is in normal operation spaced from and in alignment with the co-operating corrugated plate 27 on the shell member 23. The plate 53 is detachably connected to the truncated, cone shaped member 52 by means of suitable fastening members 54. Securely attached to the upper surface of the truncated, cone shaped member 52 is a downwardly and outwardly inclined member 55, having attached thereto a plurality of distributing or supporting elements 56 for the purpose of receiving and distributing the grain from the spout 18, just before it enters between the corrugated grinding members 27 and 53.

In the lower portion of the shell member 23 is adapted to be located a paddle member 57, keyed to the shaft 38 by means of key 46, and adapted to revolve therewith. The paddle 57 is provided with a downwardly extended sleeve bearing 58, which revolves freely in a bracket journal 59, fastened to the frame or supporting plate member 5.

From an opening 60 in the plate 5, is adapted to extend a delivery spout 61 for the ground grain, which is guided into the chute or spout 61 by means of the revolving paddle member 57. The driving pulley 47, sprocket wheel 49, and paddle member 57 are positioned upon the shaft 38 in such a manner that

the shaft 38 may have easy adjustability upwardly and downwardly as may be desired without disturbing the relative position of the driving pulley 47, sprocket wheel 49 and the paddle 57, which are retained in operative position by means of bracket members 62, 63, or otherwise, and the supporting plate 5 for the paddle element 57.

In this construction it is readily apparent that the plate 5 functions in part as a bottom plate member for the shell 23, the lower edge of the shell 25 being suitably located in relationship to the plate member 5 in order to allow for the desired sideway adjustability of the shell 23, it being understood in this respect that the sideway adjustability is intended to keep shell 23 in perfect alignment with cone member 52.

In order to provide means for giving upward and downward motion to the shaft 38 and incidentally to the truncated cone member 52, it is preferred that the rod element 40 be mounted at each end in adjustable elements 66 and 67, which are arranged to receive in secured relationship therein manually operated rod members 68 and 69, provided at the lower ends with gears 70 and 71, securely keyed thereto and adapted to mesh with and cooperate with gear members 72 and 73, keyed to shaft 74, which is mounted in the supporting members 1 and 2, as disclosed at 75 and 76.

The upper ends of the rods 68 and 69 may be provided with hand wheels 77 and 78. Suitable bracket journal elements 79, 80, 81 and 82 are securely fastened to the frame members 1 and 2 for the purpose of maintaining the rods 68 and 69 in rotative position. By turning the wheels 77 and 78, it is apparent that the threaded portions 83 and 84 on the rods 68 and 69 will cause the rod 40 to move upward or downward as desired, thereby functioning to provide the required adjustability in the position of the corrugated plate 53, the set screws 25 and 25' also functioning to produce cooperating adjustability in order to obtain the most efficient spacing and alignment between the two corrugated surfaces 27 and 53.

The rod 40 is securely mounted thereon adjacent the frame supports 1 and 2. Guiding members 85 and 86 adapted to cooperate in slidable relationship with guiding rail members 87 and 88 are attached to the frame supports 1 and 2, thereby providing efficient means for positively guiding the rod 40 and the shaft 38 in its upward and downward movement whenever the hand wheels 77 and 78 are revolved.

This invention provides a vertical grinding machine particularly adapted for grinding corn, oats, rye and the like into feed for farm animals such as cattle, horses, hogs and other stock.

The corrugated grinding plates or mantels

may be easily removed for repairs, re-corrugated, or the like, without seriously disturbing the machine.

One of the most advantageous features of the grinding machine, according to this invention, is that the corrugations are vertically arranged on both the cone and shell members, starting out at the top or at the point of larger circumference with approximately six cuts to the inch and narrowing down to approximately sixteen cuts to the inch at the lower end. Obviously, the number of cuts so far as the corrugations are concerned may be varied without affecting the spirit of the invention; furthermore, it has been found that this particular type of corrugation taken in connection with the adjustable features of both the shell and the inner truncated cone shaped member are extremely efficient in combination with the means provided for revolving the corrugated shell in one direction and the inner truncated cone shaped member in the opposite direction, thereby increasing the grinding capacity and reducing the power consumption. Furthermore, this invention provides a complete grinding apparatus consisting of feeding means for the grain, including a distributing paddle and guides, corrugated grinding members, adjustable features for both the shell and inner cone, and a delivery element, all in one machine or a single unit.

It will be understood that many changes and modifications may be made in the form of embodiment of this invention within the scope of the following claims without departing from the spirit of the invention.

What I claim is:

1. A feed grinding machine comprising a main body member, an inlet chute for the feed mounted thereon, a rotatable paddle member within the chute for separating the feed, a shell member rotatably mounted on the main body portion and having a corrugated plate detachably connected to its inner surface, a main shaft element rotatably and adjustably mounted for upward and downward movement on the main body portion, a supporting element securely mounted on the main shaft and having detachably secured thereto a corrugated plate in operable alignment with the corrugated plate on the inner surface of the shell, means for driving in opposite directions the two corrugated plates, the adjustable means for the main shaft consisting of a supporting rod for the shaft slidably arranged in the main body portion for giving upward and downward movement, means for giving desired sideway and lock movement to the shell, consisting of adjusting and lock screws arranged around the lower periphery of the shell and supporting plate thereof.

2. A feed grinding machine comprising a main body member, an inlet chute for the

feed mounted thereon, a rotatable paddle member within the chute for separating the feed, a shell member rotatably mounted on the main body portion and having a corrugated plate detachably connected to its inner surface, a main shaft element rotatably and adjustably mounted for upward and downward movement on the main body portion, a supporting element securely mounted on the main shaft and having detachably secured thereto a corrugated plate in operable alignment with the corrugated plate on the inner surface of the shell, means for driving in opposite directions the two corrugated plates, the adjustable means for the main shaft consisting of a supporting rod for the shaft slidably arranged in the main body portion for giving upward and downward movement, means for giving sideway movement to the shell, consisting of adjusting and lock screws arranged around the lower periphery of the shell and supporting plate thereof, ball bearing members for the lower ends of both the shell and the main shaft members.

3. A feed grinding machine comprising a main body member, an inlet chute for the feed mounted thereon, a rotatable paddle member within the chute for separating the feed, a shell member rotatably mounted on the main body portion and having a corrugated plate detachably connected to its inner surface, a main shaft element rotatably and adjustably mounted for upward and downward movement on the main body portion, a supporting element securely mounted on the main shaft and having detachably secured thereto a corrugated plate in operable alignment with the corrugated plate on the inner surface of the shell, means for driving in opposite directions the two corrugated plates, the adjustable means for the main shaft consisting of a supporting rod for the shaft slidably arranged in the main body portion for giving upward and downward movement, means for giving desired sideway movement to the shell, consisting of adjusting and lock screws arranged around the lower periphery and supporting plate thereof, ball bearing members for the lower ends of both the shell and the main shaft members, and members connected with the main body portion for retaining the upper periphery of the shell member in proper alignment during its rotation.

In testimony whereof, I affix my signature.
FRANK M. MAYER.
